(57) **CLAIM**

The ornamental design for an electric fishing reel remote control as shown and described.

DESCRIPTION

The file of this patent contains at least one drawing executed in color. Copies of this patent with color drawings will be provided by the Office upon request and payment of the necessary fee.

FIG. 1 is a front, right-side, bottom perspective view of an electric fishing reel remote control, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front, right-side, bottom perspective reference view showing a state of use.

The red coloring in FIG. 8 indicates environment and forms no part of the claimed design.
